UNITED STATES PATENT OFFICE.

LAURENCE M. OAKLEY, OF TRENTON, NEW JERSEY. ASSIGNOR TO ESSEX RUBBER COMPANY, OF TRENTON, NEW JERSEY, A CORPORATION OF NEW JERSEY.

SHOE SOLE.

Application filed March 6, 1922. Serial No. 541,369.

To all whom it may concern:

Be it known that I, LAURENCE M. OAKLEY, a citizen of the United States, and a resident of Trenton, county of Mercer, State of New Jersey, have invented an Improvement in Shoe Soles, of which the following is a specification.

The present invention relates to molded composition soles for boots and shoes. The object of the invention is to provide an anti-slipping sole for shoes for general sport wear and more particularly a sole which will effectively grip surfaces of different types, such as sod, dirt, wet stones and smooth floors, not only when the sole is new but after it has worn.

The nature and objects of the invention will be best understood from a description of a particular illustrative embodiment thereof. For the purposes of such description reference will be made to the accompanying drawings, in which

Figure 1 is a plan view of a shoe sole constructed in accordance with the principles of the invention;

Figure 2 is a sectional view taken on the line 2--2 of Figure 1.

The sole shown for the purposes of illustration is an outer sole adapted to be incorporated in any desired shoe but designed more especially for sport shoes. It is made preferably of rubber or some similar suitable composition molded into desired form and vulcanized to such an extent as will give it the desired stiffness. Anti-slipping devices are suitably arranged over a desired area of the sole, including the heel; for example, over the ball portion.

These devices are of a character to present projections adapted to penetrate into softer materials, such as soft soil and the like to afford a suitable grip to prevent slipping, and suction cups which are so arranged as to become effective as such when the sole engages a hard surface. The suction cups preferably are of such character that in soft ground they act as projections to grip the ground and on hard surfaces they act after the usual manner of suction

The anti-slipping devices illustrated comprise suction cups and projections which preferably extend beyond the plane of the cups. The suction cups may be of any suitable form. As shown, annular projections 5 form the cups which are made deeper by recesses 6 in the body of the sole. The recesses have the effect of causing the suction cups to remain as operative elements even after the annular projections are entirely worn away in use.

When a shoe having the sole shown engages a hard smooth surface the projections 7, if yieldable as in the preferred structure, will be deformed or bent to bring the suction cups into contact with the surface and therefore into operation to prevent slipping. When engaging soft ground the projections 7, as also the annular projections 5, penetrate into the ground to grip the same.

The arrangement shown, in which the projections are within the vacuum cups, presents the advantage that the yielding and flexing movements of the projections have a tendency to dislodge any dirt which may cling within the cups and furthermore the recesses 6 in the sole effect an additional lengthening of the projections and causes the relation of vacuum cup and projection to be maintained as the sole wears.

The degree of flexibility of the material of the sole will depend upon the use for which it is primarily designed. Preferably a material is selected for the sole as a whole, which will afford the desired resiliency in the annular projections which form the vacuum cups and in the central projections so that it will not be necessary to combine material of different qualities in a sole.

Various possible embodiments may be made of the invention and various changes in the embodiment described within the scope of the subjoined claims.

I claim as my invention:

1. A flexible composition shoe sole having annular projections forming vacuum cups and central yieldable projections within said annular projections extending beyond the plane thereof, the sole being recessed within the annular projections below

its normal surface substantially as and for the purposes described.

2. A shoe sole of molded resilient composition having a series of vacuum cups distributed over the area of the sole, each cup comprising an annular ring projecting beyond the normal plane of the sole and a depression within said ring which extends into the body of the sole, together with a central

10 projection within the annular ring extend-

ing beyond the plane of the ring, said projection being resilient whereby it will yield to the plane of the annular ring under a predetermined pressure and the vacuum cup will be brought into operation.

15

In testimony whereof, I have signed my name to this specification this third day of March, 1922.

LAURENCE M. OAKLEY.
